FIG. 1.

Des. 195,648

PAGE 2

FIG. 2.

FIG. 3.

FIGURE 1 is a perspective view of a combined television receiver and screen cover therefor, showing my new design;

FIGURE 2 is a front perspective view with the screen cover removed; and

FIGURE 3 is a rear perspective view with the screen cover in place.

The side not shown is like the side disclosed. The dominant features of my design reside in the portion shown in full lines.

I claim:

The ornamental design for a combined television receiver and screen cover therefor, as shown and described.
